UNITED STATES PATENT OFFICE.

MARY E. HEINRICH, OF FREEPORT, NEW YORK.

SPORT-COSTUME.

1,396,203.

Specification of Letters Patent.

Patented Nov. 8, 1921.

Application filed May 21, 1921. Serial No. 471,392.

To all whom it may concern:

Be it known that I, MARY E. HEINRICH, a citizen of the United States, and resident of Freeport, Long Island, in the county of 5 Nassau and State of New York, have invented certain new and useful Improvements in Sport-Costumes, of which the following is a specification.

The invention relates to improvements in 10 sport costumes and particularly to knickerbockers having panels arranged in connection therewith to give the appearance of a skirt while permitting free movement of the limbs. Preferably front and back panels 15 are provided and are adapted to be detachably secured to a belt, or the like, which may be buttoned on at the top of the knickerbockers, the panels then preferably being buttoned, or otherwise suitably secured to 20 the upper portion of the knickerbockers, so as to permit the lower portions of the panels to hang free. In the preferred construction plaited panels are employed which are so arranged as to provide outer folds of material 25 having adjacent vertical edges, which are adapted to hang together, other portions of the panel being arranged to the rear of the opening so provided that a fold, or portion of the panel will always remain in position, during movement of the limbs, to 30 preserve the appearance of a skirt.

The object of the invention is to provide an improved construction of the character briefly referred to above.

35 In order that the invention may be more clearly understood, attention is hereby directed to the accompanying drawings forming part of this application and illustrating certain embodiments of the invention. In 40 the drawings,

Figure 1 represents a front elevation of a pair of knickerbockers with a plaited panel secured thereon, embodying one form of the invention;

45 Fig. 2 is a front elevation of a pair of knickerbockers having a plain panel secured thereon, constituting a modified form of the invention.

Fig. 3 is an enlarged cross section taken 50 on the line 3—3 of Fig. 1, through one of the two members of which the plaited panel shown in Fig. 1 is formed;

Fig. 4 is a similar section taken on line 55 4—4 of Fig. 1, through the other member of which the plaited panel is formed;

Figs. 5 and 6 represent the sheets of ma-

terial from which the two members of the panel shown in Fig. 1 are formed;

Fig. 7 is an enlarged cross section taken on line 7—7 of Fig. 8;

Fig. 8 is an enlarged front elevation of the panel shown in Fig. 1, certain parts being broken away, and

Figs. 9 and 10 are detail views, somewhat diagrammatic and partly broken away, illustrating the manner in which the two members constituting the plaited panel are connected together at their upper portions.

Referring to the drawings, the construction comprises a pair of knickerbockers 1 which preferably are provided with cuffs 2 at the bottom over which boots or golf stockings may be drawn.

Various types of panel may be used to complete the costume. In Fig. 2 I have 75 illustrated a plain panel 3 which is secured at its upper edge to a belt 4, which may be secured to buttons 5 at the top of the knickerbockers. Preferably the belt is made in two portions, a rear portion which carries a 80 panel (not shown) exactly similar to the panel 3, this rear belt being buttoned on buttons 5, after which the front belt portion carrying the front panel 3 may be buttoned on buttons 5. Panel 3 is preferably provided with button holes along its edges by 85 which it may be secured to buttons 6 on the knickerbockers. The panel is thus fastened to the knickerbockers for a portion of its length and is adapted to hang free below 90 such portion. When it is not desired that the panel should be detachable it may, of course, be sewed, or otherwise secured to the knickerbockers. The bottom edge 7 of the panel should hang in alignment with the 95 bottom of the full portion of the knickerbockers indicated at 8 immediately above the cuffs 2.

The plaited panel 3¹ shown in Fig. 1, may be, and preferably is carried by belt sections 100 and buttoned, or otherwise secured to the knickerbockers in the manner described in connection with the plain panel.

Preferably each plaited panel, that is either the front panel or the rear panel, is 105 made from a lefthand member 9 and a righthand member 10 which are shown in Figs. 5 and 6. Member 9 is provided with a cut-out portion 11 at the upper part of its righthand edge, a portion 12 of the material 110 being accordingly provided beneath the cut-out 11 which is intended to be folded under

to the left along the line indicated at 15. The righthand member 10 is likewise provided with a cutout portion 13 at the upper part of its lefthand edge, whereby a portion 5 of material 14 is provided beneath cutout 13 which is intended to be folded under to the right, along line 16. The material of member 9 is to be folded along the various dotted lines indicated thereon, and the material of member 10 is to be folded along the various dotted lines indicated thereon, as will be more fully explained hereinafter.

When the two members of the panel are to be secured together, the portion 12 of member 9, and the edge portion 17 adjacent to cutout 11, above the same, are folded under along line indicated at 15, portion 14 of member 10 being folded under to the right along line 16. The edge of portion 17 10 is then stitched over the vertical edge portion 18 of member 10, adjacent the cutout 13, this stitching being indicated by the line 19. The material of member 9 is then stitched in a horizontal line to the underlying horizontal edge portion 20 of member 10, at the bottom of cutout 13, as is indicated in Fig. 9 at 21. The vertical center line of the panel is indicated in the various figures at 22, from which it will be noted that the portion 17 of member 9 is secured over the portion 18 of member 10 a short distance to 25 the right of this center line.

The manner in which member 10 is folded to produce the desired plaited effect is indicated in Figs. 3 and 8. Beginning at the righthand edge, 22, of the member the material extends to the right for a short distance and is then folded back upon itself along line 23, the outer portion of the material 30 being indicated at 24. After extending for a distance to the left the material is folded back upon itself along line 25, the overlying material, 26, extending to the right until it is again folded over upon itself along line 27, the overlying fold of material, 28, 35 extending to the left until edge 29 is reached, from which line the material is folded back under itself, as is indicated at 30, until edge 31 is reached, the material again extending to the left, as is indicated at 32, from edge 31 until the outside edge 16 is reached, from 40 which point the material, as indicated at 14, is again folded back under itself. The under outside fold extending from edge 22 to the folding line 23 is stitched along its edge, as is indicated at 33, to the overlying material 24, and the underlying fold 14, at the opposite edge of member 10, is stitched adjacent to its edge to the overlying fold 32, as 45 is indicated at 34.

Member 9 is folded in a similar manner to member 10, and, beginning with the lefthand edge of member 9, it comprises folds 35, 36, 37, 38, 39, 40 and 12. The outside 50 underlying fold 35 may be stitched along its

edge to the overlying fold 36, as is indicated at 41, and the underlying fold 12 at the opposite edge of the member may be stitched along its edge, as is indicated at 42, to the overlying fold 40.

It will be seen that the arrangement described provides a pair of box plaits in front, one on each side of the center line 22, having the front folds 28 and 38 respectively, and a pair of plaits, or members 75 which, when fastened on the knickerbockers, give the appearance of plaits, 24 and 36, respectively, adjacent the two edges of the panels. The two box plaits have their edges 80 29 and 43, respectively, hanging adjacent to each other at the vertical center line of the panel and the knickerbockers. The box plaits are stitched, adjacent their vertical edges 29 and 43, to the underlying material, namely, fold 40 of members 9, for a 85 distance which extends down from the top for a distance about equal to the vertical line of stitching 19 shown in Fig. 10, that is, to a point just below the bottoms of the cutouts 11 and 13.

It will also be noted that folds of members 9 and 10 are interleaved together, fold 40, 12, of member 9 being immediately behind the vertical opening between the box plaits, fold 40, 12, being interleaved or inserted between plait 25, 30, in front and fold 32, 14, of member 10, at the rear. This arrangement permits free movements of the limbs while preserving the appearance of a 90 plaited skirt.

It will be understood that the invention is not strictly limited to the details of construction described but is as broad as is indicated by the accompanying claims.

What I claim is:

1. In a sport costume, the combination of knickerbockers, a belt adapted to be detachably secured at the top thereof and removable therefrom, and panels secured to said belt to hang down over the knickerbockers, 100 said knickerbockers and panels having co-acting means for securing the upper portions of the panels to the knickerbockers, to permit the lower portions of the panels to hang free.

2. In a sport costume, the combination of 115 knickerbockers, a belt adapted to be detachably secured at the top thereof and removable therefrom, and a plaited panel secured to said belt to hang down over the knickerbockers, said panel being formed of two 120 members secured together at their upper portion and hanging down below said portion with a fold of one extending between folds of the other, said members having outer folds hanging freely in front of said first 125 named fold with adjacent vertical edges adapted to hang together.

3. In a sport costume, the combination of knickerbockers, and panels hanging down at the front and rear thereof and removable 130

therefrom, each panel being secured to the knickerbockers at its upper portion, and being plaited with interleaved folds adjacent its vertical center line so arranged as to permit free movement of the limbs while preserving the appearance of a skirt.

4. In a sport costume, the combination of knickerbockers, and panels hanging down at the front and rear thereof and removable therefrom, each panel being formed of two members secured together at their upper portion and hanging down below said portion with a fold of one extending freely between folds of the other, said members having outer folds hanging freely in front of said first named fold with adjacent vertical edges adapted to hang together, each panel being secured to the knickerbockers at its side edges for a portion only of the vertical distance from the top thereof.

5. In a sport costume, the combination of

knickerbockers and a panel hanging over the same in front, formed of two members folded along vertical lines, under folds of the members being secured together along a vertical line, at one side of the center line of the panel, for a short distance from the top, said members being folded to provide box plaits in front having edges which hang adjacent to each other at the vertical center line, said edges being secured to the underlying material for a distance from the top, and hanging freely for the distance below the same, and one member having a fold which extends behind the opening between said edges and is inserted between the box plait of the other member and an underlying fold of said other member.

Signed at New York city, in the county of New York and State of New York, this 16th day of May, A. D. 1921.

MARY E. HEINRICH.
